COIN CONTROL MECHANISM

Paul Moos, Zug, Switzerland, assignor to Landis
& Gyr, A-G., a corporation of SwitzerlandApplication March 11, 1933, Serial No. 660,341
In Switzerland March 17, 1932

6 Claims. (Cl. 194—1)

The present invention relates to coin controlled mechanism, and more particularly to a novel and improved coin control device for use with automatic vending machines, prepayment meters and the like.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawing, referred to herein and constituting a part hereof, illustrates one embodiment of the invention, and together with the description, serve to explain the principles of the invention.

Of the drawing:

Figure 1 is a front elevation of a portion of an automatic vending machine or other coin controlled device embodying the present invention, and with the cover plate, handle and certain other parts removed;

Figure 2 is a vertical section of the embodiment shown in Figure 1;

Figure 3 is a section taken on the line 3—3 of Figure 2; and

Figure 4 is a detailed perspective view of a modified form of one of the elements shown in the other figures.

The present invention has for its object the provision of a coin control device provided with means for preventing the insertion of a second coin before the completion of the operation to be effected by the insertion of a first coin. Another object is the provision of means for obstructing the coin-receiving slot so long as an unused coin remains in operative position within the machine.

In accordance with the illustrative embodiment of the invention, a coin receiving slot is provided which communicates with a pathway through which the coin moves to the actuating mechanism, where the coin couples a member for movement by means of an external handle or knob. The presence of a coin in the guideway prevents displacement of an obstructing member and so reduces the effective size of the slot as to prevent insertion of another coin until after the first coin has been released. A second slot obstructing member is also provided and is

moved to close the slot by movement of the handle or knob from its normal position.

It will be understood that the foregoing general description and the following detailed description as well are exemplary and explanatory of the invention but are not restrictive thereof.

Referring now in detail to the illustrative embodiment of the invention as shown by the accompanying drawing, the casing 1 of the vending machine or other coin-controlled mechanism is partitioned off by walls 2 and 3 to provide a space, open at the bottom, within which is positioned a coin-receiving and coupling device. Near the top of this space, the casing 1 is formed with a coin-receiving slot 4, communicating with a fixed coin chute or guideway 5, the bottom of which opens into a coin pocket 6 which is rotatably mounted about a horizontal axis. A slot obstructing member 9, formed from a flat bar and bent to form nearly a right angle, is pivotally mounted by means of pivot pin 8 on lug 7 projecting outwardly from one wall of the fixed guideway. Slot obstructing member 9 has its upper portion extending substantially horizontally, and at its front end is bent to one side to provide a finger 10 which lies directly behind slot 4 and near the upper end of said slot. The downwardly extending portion of member 9 is bent away from the fixed guideway, as shown in Figure 3, and at its lower end is bent inwardly towards said guideway to provide a finger 11 projecting into the space between the lower end of guideway 5 and the coin pocket 6.

Pivotedly mounted on the upper portion of the guideway 5 is a bar 12 provided with a small projection 13 by which it can be variably positioned to register with any of the depressions 14 which are formed on one wall of that guideway. Bar 12 is set at the desired position in accordance with the size of coin to be used in the device, and forms a stop limiting movement of the oscillatory member 9 and against which the finger portion 11 of that member is held by spring 15.

Slot 4 is preferably formed of such a size as to receive the largest coin to be employed with the machine, and this slot is reduced to one of the proper size for a particular coin by means of a slot 18 formed in cover plate 16 which is secured to the casing 1 by means of screws 17, with the slots 18 and 4 in register.

A handle or knob is provided for actuating the device and for this purpose, a drum 20, pinned to shaft 19 is rotatably mounted by this shaft in the cover plate 16, and is connected to knob 22 by means of spring 23. Spring 21 having one of its

ends fastened to drum 20, and its other end fastened to shaft 19, is provided for returning the drum and shaft to normal position, while the spring 23 frictionally couples knob 22 to shaft 19.

- 5 At its inner end, and cooperating with the coin pocket 6, shaft 19 is provided with a centering pin projecting into a socket 27 in coin pocket 6, and is also provided with a segmental finger 25 which, in its normal position, has its free end 10 lying outside the path through which the coin moves to the coin pocket.

The coin pocket 6 is rotatably mounted at its front end on pin 24, and at its rear in wall 2, and is provided with a wing piece 28 extending into the inner portion of the vending machine or other coin control mechanism and serving to couple the pocket to said mechanism.

Means are provided for preventing operation of the mechanism by coins which are not of the proper size, and a plate 29 is secured to the walls of pocket 6 and may be variably positioned therein. Plate 29 cooperates with the forward portion of the pocket 6 to form a support for coins of the proper size, while smaller coins fall through the space between said plate and forward portion. By properly dimensioning slot 18 and the space between plate 29 and the front of the pocket, the mechanism can be arranged to operate with only a particular size of coin.

30 Means are provided for obstructing and completely closing slots 4 and 18 when knob 22 is turned from its normal position, and for this purpose, an arm 30 is pivotally mounted on the inner side of the casing by means of bolt 17, and is normally held in the position shown in Figure 1 by means of spring 31. In this position, the upper end of arm 30 lies to one side of slot 4, while the mid portion of said arm rests with its shoulder 32 directly against the flat surface 26 formed on coin pocket 6. As shaft 19 is turned and pocket 6 is rotated thereby, arm 30 is moved to a position directly in back of slot 4, thereby preventing the insertion of any coins.

In the operation of the embodiment shown in Figures 1 to 3 of the drawing, a coin inserted through slot 18, passes through guideway 5 to the coin pocket 6, and bar 12 guides the coin to a position where it is supported by plate 29. Knob 22 is then turned and moves shaft 19 through the action of friction spring 23, bringing the segmental finger 25 into contact with the side of a coin, and thereby turning the coin pocket 6 and wing pieces 28 to operate the automatic vending or other coin-controlled mechanism. This turning of shaft 19 causes the flat side 26 of coin pocket 6 to move arm 30 to slot closing position, preventing further insertion of coins until the knob 22 has been released. When coin pocket 6 has made somewhat more than a quarter revolution, spring 31 pressing the arm 30 against the flat portion 26 exerts a toggle action thereon and continues rotation of the coin pocket 6 until it has made a half revolution, thereby dropping the coin into a suitable coin receiving receptacle within the casing.

- 65 1. Handle 22 may then be released and is returned to its original position removing the arm 30 from the position where it obstructs slot 18.

If an attempt is made to insert a second coin before handle 22 is turned, lever 9 prevents complete insertion of this coin, inasmuch as the front end 10 must be pushed aside by the second coin and this movement is prevented by contact of the lower end 11 with the coin already in pocket 6. Friction spring 23, and coil spring 21 also prevent rotation of bolt 19 while a coin is in slot 18. The

end 11 of arm 9 is of sufficient length so that the upper end 10 continues to serve to obstruct the coin slot until arm 30 has been moved into register with slots 4 and 18.

The embodiment of the invention shown in the drawing may be adapted for various sizes of coins merely by changing the cover plate 16 and by variably positioning plate 29 and bar 12.

For providing still better protection against unintentional or even malicious injury, the coin pocket 6 may be formed as shown in Figure 4 of the drawing. As shown, a comb-like piece of sheet metal 33 is attached to the side walls of the pocket 6, and spring-pressed flaps 34 are mounted on the casing 1 to normally engage the under side of combs 33. In case an attempt is made to use a coin to which a thread has been attached, the coin is properly received within the pocket 6, but upon rotation of the pocket, the thread becomes caught between the teeth of comb 33, so that an attempt to withdraw the coin by the thread results in breaking the thread, permitting the coin to fall into the coin-receiving receptacle.

The invention in its broader aspects is not limited to the specific mechanisms shown and described but departures may be made therefrom within the scope of the accompanying claims without departing from the principles of the invention and without sacrificing its chief advantages.

What I claim is:—

1. A coin control mechanism including in combination a coin-receiving slot, an actuating member to be coupled to a controlled mechanism by a coin and a finger obstructing said slot and displaceable by insertion of a coin in said slot, a second finger mounted for movement with said first finger and movable to contact with a coin in coupling position on insertion of a second coin and a slot-obstructing plate moved by said actuating member when displaced from normal position to prevent insertion of a coin while said member is displaced.

2. A coin control mechanism including in combination a coin-receiving slot, an actuating member to be coupled to a controlled mechanism by a coin and means actuated by said actuating member for closing said slot while a coin is in coupling position and said member is displaced from normal position, means for obstructing said slot and displaceable by the insertion of a coin and means cooperating with a coin in coupling position to prevent displacement of said obstructing means while a coin is in coupling position.

3. A coin control mechanism including in combination a coin-receiving slot, an actuating member to be coupled to a controlled mechanism by a coin, a finger obstructing said slot and displaceable by insertion of a coin in said slot, a second finger mounted for movement with said first finger and movable to contact with a coin in coupling position on insertion of a second coin, means for releasing said first coin on movement of said actuating member and thereby permitting movement of said fingers, and a slot closing member moved by said actuating member and brought into operation by movement of said member before said fingers are released whereby insertion of a coin is prevented while an unused coin is in said mechanism or said actuating member is displaced from normal position.

4. In a coin control mechanism the combination of a rotatable coin receiving pocket, an actu-

ating handle to be coupled thereto by a coin in said pocket, a comb like member mounted on said pocket and a guard mounted adjacent said comb for guiding a thread between the teeth of said 5 comb.

5. In a coin control mechanism the combination of a rotatable coin receiving pocket, a rotatable actuating knob coupled to said pocket by a coin in said pocket, a member mounted on said 10 pocket and provided with means for engaging a thread attached to a coin.

6. In a coin control mechanism the combination of a rotatable coin receiving pocket, a rotatable actuating knob coupled to said pocket by a coin in said pocket, a member mounted on said pocket and provided with means for engaging a thread attached to a coin and means preventing insertion of a second coin in said mechanism while an unused coin is present or while said knob is displaced from normal position.
